I. ROSEN

GAME BOARD

Filed Feb. 28, 1927

INVENTOR
Isidor Rosen
BY Maurice Block
ATTORNEY

UNITED STATES PATENT OFFICE.

ISIDOR ROSEN, OF BROOKLYN, NEW YORK.

DESIGN FOR A GAME BOARD.

Application filed February 28, 1927. Serial No. 20,923. Term of patent 7 years,

To all whom it may concern:

Be it known that I, ISIDOR ROSEN, a citizen of the United States of America, residing at Brooklyn, Kings County, State of New York, have invented a new, original, and ornamental Design for a Game Board, of which the following is a specification, reference being had to the accompanying drawing, forming a part hereof, in which the

I claim—

The ornamental design for a game board as shown.

Signed at New York city, New York, this 23 day of February, 1927.
